ABSTRACT OF THE DISCLOSURE

An improved tool used for crimping a primer in the end of a cartridge casing. The tool includes a body mounted on a reciprocally movable press platen. The tool body has a bore formed therein, and a punch assembly is mounted within the bore. A chamber is defined within the closed end of the bore, and more particularly, between the closed end of the bore and the inner end of the punch assembly. During the operation of the tool, the chamber is filled with pressurized hydraulic fluid. This fluid in the chamber permits movement of the punch assembly, relative to the tool body, during the portion of the stroke of the press platen during which the punch assembly is in contact with the cartridge casing. The chamber is connected with a pressurized fluid reservoir which, in the preferred embodiment, is mounted on and moves with the body. The reservoir is finned to assist cooling the fluid therein, and the fluid passages which interconnect the reservoir and the chamber are formed in the tool body so as to minimize the possibility of any leakage of pressurized fluid and to minimize maintenance of the tool.

BACKGROUND OF THE INVENTION

This invention relates to an improved crimping tool, and more specifically, to an improved tool for crimping a primer in the end of a cartridge casing.

In the past, cartridge cases, and particularly .30 caliber cartridge cases, have been manufactured in a multi-step process. In this process, the cartridge cases to be manufactured are placed on separate mandrels and the mandrels are adapted to be sequentially moved to a plurality of work stations beneath a reciprocally movable platen of a press. The press platen has a plurality of tools mounted thereon which are utilized to perform various operations or steps on the cartridge casing in connection with the manufacture of the casing.

The tool previously used for crimping primers in the ends of cartridge casings in such a process included a punch and Bellville spring assembly which were mounted on the press platen. The spring assembly was positioned so as to permit limited relative movement of the punch with respect to the press platen during the time the punch was in contact with the cartridge casing. The spring assembly was necessary because the thickness of the end walls of the cartridge casings is not set forth in the government specifications and some variation in the end wall thickness occurs.

However, there have been several problems with this prior crimping tool. To achieve satisfactory operation, i.e., to produce finished cartridge casings within the rigid government specifications, the setting of the spring assembly had to be frequently and carefully adjusted to prevent defective casings from being manufactured. The required checking of the adjustment and the adjustment itself were time consuming and thus increased the cost of manufacturing the casings. Also, even when properly adjusted, the prior crimping tool often would cause minute cracking in the end walls of the casings or other defects, and if the primer had not been properly positioned in the preformed cavity in the end wall, the tool

2

could not correctly crimp the primer in the casing. Any manufacturing defects in the cartridge casing are significant in view of the stringent government specifications.

SUMMARY OF THE INVENTION

In contrast, the improved crimping tool of the present invention provides satisfactory, substantially defect-free operation and significantly minimizes, relative to the prior tools, the amount of the maintenance, and the frequency of adjustment required for satisfactory operation. The crimping tool of the present invention includes a tool body which is mounted on and carried by the press platen and which has a bore formed therein so that the central longitudinal axis of the bore is coaxial with the central longitudinal axis of the cartridge casing to be crimped by the tool. A punch assembly, including a punch, is mounted in the bore so that a chamber is formed in the bore between the assembly and the closed end of the bore. During operation, the chamber is maintained full of pressurized fluid therein permit the punch assembly to move relative to the tool body during the time the punch is in contact with the cartridge casing.

The use of the hydraulic chamber provides unexpectedly advantageous results in that the punch may be in contact with the cartridge casing during a significantly longer portion of the stroke of the press platen. This permits the punch initially to contact the casting at a higher velocity and provides superior work hardening and cold working characteristics.

In the preferred embodiment, a pressurized fluid reservoir is also mounted on and carried by the tool body so that the reservoir reciprocally moves with the press platen. The reservoir has a plurality of fins formed thereon to assist in cooling of the fluid in the reservoir. The tool body also includes a plurality of passages interconnecting the reservoir and the chamber, and these passages minimize the possibility of leakage of pressure fluid from the tool body and minimize maintenance of the tool.

A relief and check valve combination is positioned, in the preferred embodiment, within the reservoir and is used for controlling the flow of fluid to and from the chamber in the bore. The reservoir is also connected with an external source of gas or air under pressure, and the coupling interconnecting the air hose and the reservoir is arranged and designed so as to be easily removable so that when removed, an adjusting tool may be inserted in the reservoir for the purpose of adjusting the setting on the valve assembly.

In some embodiments, and particularly those tools wherein a relatively large volume of hydraulic fluid is displaced because, for example, the bore, and thus the chamber, has a relatively large diameter and/or the speed of the press is relatively high, the passages in the tool body may be formed and arranged so that the fluid may be recirculated between the reservoir and hydraulic chamber so as to minimize the heating of the fluid in the chamber. This recirculation of the fluid also helps to disperse any foreign material which may get into the fluid.

Accordingly, it is one of the principal objects of the present invention to provide an improved tool for crimping the primers in the ends of cartridge casings. A related object of the present invention is to provide an improved tool of the type described wherein the tool includes a chamber formed in the tool body between the punch assembly and the tool body, and wherein the chamber permits the punch assembly to move relatively with respect to the tool body and significantly improves the operation of the crimping tool.

Another object of the present invention is to provide an improved tool for crimping primers in the ends of cartridge casings wherein the crimping tool is mounted

on and carried by a reciprocally movable press platen; wherein the tool includes a bore whose central longitudinal axis is coaxial with the central longitudinal axis of the cartridge casing to be crimped; wherein the punch assembly is mounted in the bore; wherein a chamber is formed in the closed end of the bore between the punch assembly and the closed end of the bore; wherein the chamber is maintained full of pressurized fluid; and wherein the chamber and punch assembly are arranged so that the punch assembly may move relatively with respect to the tool body during the time the punch assembly is in contact with the cartridge casing.

Still another object of the present invention is to provide an improved tool for crimping primers in the ends of cartridge casings wherein a pressure reservoir is mounted on the tool, and thus on the press platen, for movement therewith; wherein the tool body has a number of passages formed therein which interconnect the chamber and the reservoir; and wherein valve means are positioned in the reservoir for controlling the pressure of the fluid in the chamber and the flow of fluid to and from the chamber and the reservoir. A related object of the present invention is to provide an improved tool of the type described wherein the reservoir has a plurality of fins formed thereon to assist in the cooling of the fluid in the reservoir; and wherein the reservoir has an aperture therein which is normally adapted to be closed by a coupling means for connecting the reservoir to a source of pressurized gas or air and which is designed so that when open, access to the valve means in the reservoir for adjustment thereof is permitted through the aperture. A further related object of the present invention is to provide an improved tool of the type described wherein fluid passages in the tool body are arranged to permit recirculation of the fluid between the reservoir and the chamber so as to assist in cooling the fluid in the chamber.

These and other objects of the present invention will become apparent from the following description of the preferred embodiment and the appended claims.

DESCRIPTION OF THE DRAWINGS

FIG. 1 is a partial, vertical cross-sectional view of the improved tool of the present invention showing the tool mounted on a press platen and positioned above a cartridge casing to be manufactured.

FIG. 2 is a vertical cross-sectional view of a portion of the improved tool of the present invention showing the details of the punch assembly and chamber.

FIG. 3 is a partial, vertical, cross-sectional view taken along the lines 3—3 in FIG. 1.

FIG. 4 is a partial, cross-sectional view of a modified embodiment of the improved tool of the present invention showing a modified chamber and interconnecting passage arrangement.

FIG. 5 is a diagram showing the position of the press platen and thus the improved tool of the present invention, with respect to time during a stroke of the press platen.

DESCRIPTION OF THE PREFERRED EMBODIMENT

Referring now to FIGS. 1, 2 and 3, the improved tool of the present invention comprises a body, shown generally at 11, which includes a generally cylindrical member 12 and an arm 13. A plurality of bolts, one being shown at 14, are used to mount the body 11 on a platen 15 of a press, not shown, so that the upper cylindrical member 12 of the body is positioned in a cylindrical cavity 16 formed in the press platen.

The structure and mode of operation of the press is conventional, and therefore a detailed description of the press has not been included herein. In summary, however, the press causes the press platen 15 to be moved reciprocally through a stroke of a preselected fixed distance and at a preselected fixed distance and at a pre-

selected rate, e.g., one hundred strokes per minute, in a conventional manner. Also, as noted above, the press platen 15 may have a number of other tools mounted thereon which are utilized in the manufacture of cartridge casings, and the body 11 would be mounted on the press platen with respect to these other tools so that there is no interference or contact between the various tools.

A pressurized reservoir 17 is mounted on the upper face 18 of the arm 13 by a plurality of bolts, not shown, so that the reservoir 17 moves reciprocally with the press platen 15 and so the reservoir 17 is maintained vertical, as shown, during operation of the press. A central, circular aperture 21 is formed in the lower end 22 of the reservoir 17. A conventional "O" ring seal 23 is positioned in a groove 24 about the aperture 21 and forms a seal between the lower end 22 of the reservoir and the upper face 18 of arm 13. The upper end 25 of the reservoir 17 has a threaded opening 26 formed therein. A conventional fitting 27 is normally threaded into the opening 26 and includes a quick-disconnect coupling 27 which is adapted to be connected to the coupling end 28 of an air hose 29. The hose 29 is connected at its other end, not shown, with a source of air or gas under pressure. While the pressure of the air or gas may vary, normally air or gas under a pressure of 80 pounds per square inch is sufficient to permit satisfactory operation of the tool.

A plurality of fins 31 are integrally casted on the outer surface of the reservoir 17 and are designed to assist in cooling the fluid in the reservoir by increasing the rate of heat transfer during the movement of the reservoir with the press platen 15.

As best shown in FIGS. 1 and 3, the arm 13 includes a centrally located, horizontally disposed passage or bore 32 which extends from the member 12 to the outer end 33 of the arm. A centrally located, vertically disposed passage or bore 34 intersects the passage 32 and its upper, threaded end 35 opens into the interior 36 of the reservoir with the longitudinal central axis of the passage 34 being coaxial with the center of the aperture 21 and perpendicular to the central longitudinal axis of the passage 32. A second off-set vertical passage or bore 37 is formed in the arm parallel to, but spaced from, the passage 34. The passage 37 also opens into the interior 36 of the reservoir 17 with the aperture 21. A transverse passage or bore 38 is formed in the arm 13 below the passage 32, and with the central longitudinal axis of the passage 38 being perpendicular to the plane including the central longitudinal axes of the passages 32 and 34. A counterbore 39 interconnects the inner ends of passages 37 and 38; and a counterbore 41 interconnects the passages 32, 34 and 38.

The outer threaded end 42 of the passage 38 is closed by a plug 43 and flow through the counterbore 39, from passage 37 to passage 38, is controlled by a one-way valve 44 positioned within the passage 38. The valve 44 consists of a ball 45 which has a diameter greater than the diameter of counterbore 39 and which is adapted to seat against the shoulder 46 formed between the inner end of the passage 38 and the counterbore 39 so that when the ball is seated, the flow of fluid from the passage 37 to the passage 38 through counterbore 39 is prevented. The ball 45 is urged against the shoulder 46 by a coil compressor spring 47 that is positioned between the plug 43 and the ball. As a result of the use of the valve 44, fluid may flow from passage 37 to passage 38, but cannot flow from passage 38 to passage 37.

A high pressure relief valve assembly 48 is threaded into the upper end 35 of the passage 34. The relief valve assembly 48 projects through the aperture 22 and into the interior 36 of the reservoir 17 and is designed and arranged to permit flow of fluid from the passage 34, and thus passage 32, into the interior 36 of the reservoir 17, only after the pressure of the fluid in these passages exceeds a preselected value. The positioning of the valve

assembly 48 in the reservoir 17 reduces the chances of unauthorized tampering with the valve assembly.

The relief valve assembly 48 includes a housing 49 having a centrally positioned, coaxial bore 51 and counterbore 52 formed therein, with a shoulder 53 being formed therebetween. A plug 54 is threaded into and blocks the upper end of the bore 51 and the upper end 55 of the housing 49 is flared outwardly, as shown, for the reason more fully described hereinafter. The counterbore 52 communicates with the passage 34 and a plurality of relatively small diameter bores, two of which being indicated at 55, to permit communication between the bore 51 and the interior 36 of the reservoir. Flow of fluid from the counterbore 52 to the bore 51 is controlled by a ball 56 which has a diameter larger than the diameter of counterbore 52 but smaller than the diameter of bore 51, and which is adapted to seat against the shoulder 53. A coil compression spring 57 is positioned in the bore 51 between the plug 54 and a back-up plate 58 adjacent to and abutting the ball 56 so that the spring 57 urges the ball 56 tightly against the shoulder 53. As noted above, the arrangement of the ball 56 and spring 57 prevents fluid from flowing from the reservoir 17 into the passage 34, and thus the passage 32, while permitting flow from the passage 34 to the reservoir only when the pressure of the fluid in the passages exceeds a preselected value.

The bias of the spring 57 may be changed by adjusting the position of the plug 54, relative to the housing 49. To facilitate making such an adjustment, the central longitudinal axis of the valve assembly 48 is coaxial with the center of the opening 26 so that when the fitting 27 is removed from the reservoir, a long-handled tool, such as a screwdriver, may be inserted through the opening 26 and used to adjust the position of the plug 54. The flared outer end 55 of the housing 49 assists in guiding and locating the end of the screwdriver with respect to the plug.

As noted above, the passage 32 extends to the end 33 of the arm. The outer end 59 of the passage is counterbored at 61 and is threaded to receive a conventional fitting 62 which is adapted to be connected to a conventional fluid pressure sensing instrument, not shown, for the purpose of ascertaining the pressure of the fluid in passage 32.

As shown in FIG. 1, a mandrel 63 is positioned immediately below the member 12 and is supported by the mandrel support structure shown generally at 64. A cartridge casing 65 is positioned on the mandrel and is supported midway between its ends by the guide 66 which may be a part of the structure 64. The upper closed end 67 of the casing includes a preformed primer cavity 68, and a primer 69 is shown positioned in this cavity. The diameter of the cavity 68 is slightly greater than the diameter of the primer 69 so, as shown, the primer is not secured within the cavity. As noted above, in conventional manufacturing setups, the mandrel 63 may be moved, relative to the press platen 15, so that various manufacturing operations may be performed on the casing 65 while it is mounted on the mandrel 63. The mechanism required to move the mandrel with respect to the platen 15 is conventional, and for this reason the mechanism is not shown and further description thereof has not been included herein. However, it should be noted that a mandrel 63 with a casing 65 positioned thereon is always fixedly positioned below the member 12 when the press platen 15 has moved downward a sufficient distance so that there is contact between the tool and the casing.

Referring now to FIG. 2, the member 12 has a central bore 71 formed therein so that when the mandrel 63 is positioned, as shown in FIG. 1, the central longitudinal axes of the bore 71 and the mandrel 63, and thus the casing 65, are coaxial.

A punch assembly, shown generally at 72, is positioned in the bore 71. The punch assembly 72 consists of an annular retainer 73 which, in part, is positioned within the

bore 71 and which is secured to the bottom surface 74 of the portion 12 by a plurality of bolts, not shown, that extend through the shoulder 75 of the retainer. The retainer 73 has a central bore 76 formed therein, and the outer diameter of the shoulder 75 is substantially equal to the outer diameter of the adjacent part of the member 12, although a part of the shoulder 75 is cut away as shown at 77.

An annular, elongated guide 78 is positioned within the bore 76. The guide 78 has a shoulder 79 formed at its upper end, with the outer diameter of the shoulder 79 being greater than the diameter of bore 76 but less than the diameter of bore 71. The guide 78 is secured within the retainer 73 by the shoulder 79. A screw 81 is fastened to the lower surface 82 of the retainer 73 and the head of this screw extends into a groove 83 formed in the lower end 84 of the guide so as to prevent the guide 78 from rotating, relative to the retainer. The end 84 of the guide, as shown, is cut away and flared outwardly so that the end 84 cannot contact the cartridge casing 65.

The guide 78 has a central longitudinal bore 85 formed therein with the upper portion 86 thereof being threaded. A first transverse bore 87 is formed in the guide and intersects the portion 86 of the bore 85. A second transverse bore 88 is also formed in the guide and intersects the lower, smooth-sided portion 89 of the bore 85.

A generally cylindrical punch 91 is positioned in the lower portion 89 of the bore 85. The punch 91 is of conventional design and is arranged in the bore 85 so that its lower end 92 projects from and beyond the lower end of the bore 85. The lower end 92 of the punch is formed so that when the punch 91 is brought into contact with the end 67 of a cartridge casing 65, the punch will force or extrude the metal adjacent the primer cavity 68 around and adjacent to the primer 69 so as to secure the primer within the cavity 68.

The punch 91 is secured within the bore 85 by a set screw 93 which is threaded in the bore 88. The position of the punch 91, relative to the guide 78, i.e., the distance the lower end 92 of the punch projects beyond the lower end of the bore 85, is regulated by a pair of set screws 94 and 95, which are threaded, end-to-end, in the upper portion 86 of the bore 85. A set screw 96, threaded in the bore 87, is used to lock the set screws 94 and 95 in place in a conventional manner, once the correct position of the set screws 94 and 95 has been established.

The punch assembly 72 also includes a disc or piston 97 which is positioned on the upper surface of the guide 78. The disc 97 may be made of metal and has a diameter substantially equal to the diameter of bore 71. A transverse bore 98 is formed in the member 12 and vents the annular space 99 in the bore 71 defined by the upper end of the retainer 73, the lower surface of the disc 97 and the shoulder 79 of the guide 78. A conventional cup seal 101 is positioned on the upper face of the disc 97 and has a diameter substantially equal to the diameter of the bore 71. The seal 101 is adapted to minimize leakage of fluid between the seal and the bore 71.

A chamber 102 is defined in the upper end of the bore 71 between the seal 101 and the inner end wall 103 of the bore. The chamber 102 communicates, through a bore 104 in the end wall 103, with a transverse passage 105. As shown in FIG. 2, the left end of the bore 105 is blocked by a threaded plug 106 and the right end thereof communicates with the upper end of a vertical bore 107. The lower end of the bore 107 is blocked by a threaded plug 108, and the bore 107 is intersected by the left end of the bore 32 which, as noted above, is formed in the arm 13.

FIG. 4 shows a modified tool wherein the passage arrangement interconnecting the chamber in the member 12 of the tool with the reservoir 17 has been changed. More specifically, a pair of passages 111 and 112 communicate with the chamber 113 at spaced points. Passage 111 communicates with check valve 44 and permits fluid to flow

from the reservoir 17 into the chamber 113. Passage 112 communicates with the relief valve assembly 48 and when the pressure in chamber 113 and passage 112 upstream from the assembly 48 exceeds the preselected bias of the spring 57, permits fluid to flow from the chamber 113 into the reservoir 17. In this modified tool, there is no fluid communication, such as provided by bore 41, between the passages 111 and 112. The ends of the passages 111 and 112 which communicate with the chamber 113 are arranged with respect to the chamber so that there is continual recirculation of the fluid in chamber 113, i.e. the fluid in chamber 113 which has become heated as a result of the operation of the tool is returned to the reservoir while "fresh", relatively cooler fluid is introduced into the chamber 113 from the reservoir, during operation of the tool. This recirculation of the fluid keeps the temperature of the fluid in chamber 113 relatively low. Thus this modified passage arrangement is particularly advantageous in tools in which a relatively large volume of fluid is displaced per unit time, such as when the chamber 113 has a relatively large diameter and for when the tool is utilized on a high speed press, e.g., a press operating at three hundred strokes per minute. Also, the recirculation of the fluid helps to dispense any foreign material which may get into the fluid.

Operation

The operation of the improved tool of the present invention is as follows: Initially and as a result of the air or gas pressure in the upper part of reservoir 17, the chamber 102, and the passages connecting the chamber with the reservoir are completely filled with hydraulic fluid. This causes the punch assembly 72, and thus the punch 91, to be in its lowermost position. When the end 92 of the punch 91 initially comes into contact with the cartridge casing 65, the upward force on the punch 91, and thus on the punch assembly 72 including the disc 97, causes the pressure of the fluid in the chamber 102 to increase. Further downward movement of the press platen 15, and thus the punch 91, further increases the pressure in the chamber 102, and thus in passages 105, 107, 32, 34 and 52, until the setting of the relief valve assembly 84 is reached, the ball 56 is unseated and fluid is permitted to escape from the chamber 102 and passages 105, 107, 32, 34 and 52 into the reservoir. This escape of fluid through the relief valve assembly 48 permits the punch assembly 74 to move upwardly in the bore 71 relative to the member 12 and in effect, extends the working time of the punch 91, i.e. the time the punch 91 is in contact with the casing. As the press platen 15 moves away from the bottom-dead-center point, a volume of relatively "cool" fluid is drawn into the chamber 102 from the reservoir through the check valve 44 to replenish the fluid forced into the reservoir 17 through relief valve assembly 48.

As noted above, the significant amount of controlled relative movement of the punch 91 permits the punch to be brought into contact with the casing 65 at a much earlier point during the downward portion of the press stroke. This permits the punch 91 initially to strike the end 67 of the cartridge casing at a much higher velocity and provides better metal cold working and work hardening of the casing. Furthermore, apparently the relative movement of the punch, with respect to the member 12, also permits the punch to correct angular misalignments of the primer 69 in the cavity 68.

FIG. 5 shows a diagram of the time-position of the press platen 15 during one complete stroke and is included herein to illustrate the difference between the points of initial contact between the punch and the cartridge casing when the improved tool of the present invention is used and when a prior crimping tool is used. More specifically, the arrow 114 indicates the direction of movement of the platen, the point 115 the top-dead-center point of the press platen, and point 116 the bottom-dead-center

point of the press platen. The point 117 indicates the time during the stroke when the punch 91 first contacts the end 67 of the casing 65 when the improved tool of the present invention is used; whereas, the point 118 indicates the time during the stroke when the punch first can be brought into contact with the end 67 of the casing, without defective crimping, when the prior crimping tools are utilized. As will be apparent from this diagram, the punch is in contact with the casing, i.e., the work time of the punch, approximately five times longer when the improved tool of the present invention is used as compared to when the prior crimping tools are utilized.

It has been found that satisfactory results may be obtained when pressure of the hydraulic fluid in the tool, i.e., in the chamber 102 and in passages 105, 107, 32, 34 and 52, is between 800 and 2500 p.s.i. during that portion of the stroke during which the punch 91 is in contact with the cartridge casing. Also, as noted above, satisfactory results have been obtained if the air or gas introduced into the upper portion of the reservoir is under 80 p.s.i. pressure. It is important, however, that the reservoir 17 be maintained vertically, as shown, and that a sufficient volume of hydraulic fluid is always maintained in the reservoir so that no air or gas is able to get into the chamber 102 or the passages interconnecting the chamber and the reservoir. In this connection, the level of the hydraulic fluid in the reservoir should always be maintained well above the upper end of relief valve assembly 48.

30 In view of the foregoing, it is apparent that the improved tool of the present invention provides significant and unexpected advantages over the prior crimping tools in that it reduces the number of defective casings manufactured; reduces the amount of time required for adjusting and 35 maintaining the tool; and improves the quality of the finished cartridge casing as a result of the superior cold working and work hardening of the casing during the crimping operation.

Obviously, modifications can be made in the improved 40 tool of the present invention. For example, the reservoir would not have to be mounted on and carried by the press platen but could be mounted at a fixed location adjacent to the platen and connected with the tool by means of flexible hoses. The difficulty with such a fixed 45 mounting is that repeated usage, e.g., approximately one hundred strokes per minute, causes the flexible hoses to wear out relatively quickly and this increases maintenance. Also, the passages interconnecting the chamber and the reservoir would not have to be formed within the arm 13 but could be separate conduits or tubes fastened to the arm. However, it is believed preferable to form these 50 conduits or passages integrally with the arm so as to minimize the possibility of leakage of the high pressure fluid. Likewise, the specific arrangement of the components 55 of the punch assembly, of course, could be changed. For example, the disc 97 could be directly secured to the guide 78.

Thus, since the invention disclosed herein may be embodied in other specific forms without departing from the 60 spirit and general characteristics thereof, embodiments described herein are therefore to be considered in all respects as illustrative and not restrictive, the scope of the invention being indicated by the appended claims, rather than by the foregoing description; and all changes 65 which come within the meaning and range of equivalency of the claims are therefore intended to be embraced therein.

I claim as my invention:

1. Apparatus for crimping a primer in the end of a cartridge case comprising: a body adapted to be secured to a press platen which is reciprocally movable through a fixed stroke, the body having a bore formed therein so that the central longitudinal axis of said bore is parallel to the direction of the motion of the press platen and coaxial 75 with the central longitudinal axis of the cartridge case,

said bore having an open end and a closed end; punch means positioned in said bore for relative movement therein in a direction parallel to the central longitudinal axis of said bore, the punch means including, at one end thereof, a punch which, in part, projects from the open end of said bore and is adapted, during a portion of the stroke of the press platen, to contact the end of the cartridge casing in which the primer is to be crimped, the punch being positioned so that its central longitudinal axis is coaxial with the central longitudinal axis of the cartridge case during at least said portion of said stroke; means for retaining the punch means within said bore, said bore defining a chamber between said closed end of said bore and the other end of the punch means; a pressurized fluid reservoir; passage means connecting said chamber with the fluid reservoir; valve means for controlling the flow of fluid between said chamber and the fluid reservoir and between the fluid reservoir and said chamber so that said chamber and passage means are filled with fluid and so that the pressure of the fluid in said chamber and passage means is always below a preselected, relatively high pressure whereby during said portion of said stroke the punch means may move, relative to the body, toward the closed end of said bore and whereby during the remainder of said stroke, the punch means is moved toward said open end of said bore.

2. The apparatus described in claim 1 wherein the fluid reservoir moves with the press platen.

3. The apparatus described in claim 2 wherein the fluid reservoir is mounted on the moves with the body; and wherein the passage means includes passages formed in the body.

4. The apparatus described in claim 3 wherein a plurality of fins are formed on the exterior surface of the fluid reservoir and are designed to assist in the cooling of the fluid reservoir.

5. The apparatus described in claim 1 wherein the passage means includes at least two separate passage means interconnecting said chamber and the fluid reservoir so that the fluid in said chamber is recirculated during operation of the apparatus.

6. The apparatus described in claim 1 wherein the valve means includes a high pressure relief valve which is mounted within the fluid reservoir and which controls the flow of fluid from said chamber to the fluid reservoir.

7. The apparatus described in claim 6 wherein the fluid reservoir is connected with a source of pressurized gas by means of a removable fitting which is normally secured in an opening in the fluid reservoir, and which may be removed so that adjustment of the high pressure relief valve may be made through said opening.

8. The apparatus described in claim 1 wherein the punch means includes a piston and seal which are positioned in said bore adjacent to said chamber; and wherein the punch means includes means for adjusting the amount the punch projects from said open end of said bore.

9. The apparatus described in claim 1 wherein the fluid reservoir is fastened to and moves with the body; wherein a plurality of fins are formed on the exterior surface of the fluid reservoir to assist in the cooling of the fluid reservoir; wherein the passage means includes passages formed in the body; wherein the valve means includes a high pressure relief valve which is mounted within the fluid reservoir and which controls the flow of fluid from said chamber to the fluid reservoir; wherein the fluid reservoir is connected with a source of pressurized gas by means of a removable fitting which is normally secured in an opening in the fluid reservoir, and which may be removed so that adjustment of the high pressure relief valve may be made through said opening; wherein the punch means includes a piston and seal which are positioned in said bore adjacent to said chamber; and wherein the punch means also includes means for adjusting the amount the punch projects from said open end of said bore.

10. The apparatus described in claim 9 wherein the passage means includes at least two separate passages interconnecting said chamber and the fluid reservoir so that the fluid in said chamber is recirculated during operation of the apparatus.
